(57) **CLAIM**

The ornamental design for an adjustable plate cake stand, as shown and described.

DESCRIPTION

FIG. 1 is a front perspective view of an adjustable plate cake stand showing our new design;

FIG. 2 is a top view thereof;

FIG. 3 is a bottom view thereof;

FIG. 4 is a side view thereof; and,

FIG. 5 is a front view thereof.

The subject matter shown in dashed lines, and any surfaces of the design not shown, including interior surfaces, form no part of the claimed invention.

1 Claim, 3 Drawing SheetsFIG. 1

FIG. 3

FIG. 2
